UNITED STATES PATENT OFFICE.

HOVAGIM SAKALIAN, OF NEW YORK, N. Y.

DOOR FASTENING.

Application filed February 6, 1926. Serial No. 86,406.

The invention relates to improvements in fastenings for house and apartment doors, and is more particularly designed to be embodied in and with main fastenings or locks applied to the inner faces of such doors and door casings and constructed to be substantially non-forceable or burglar-proof. The special form of main fastening or lock for which the invention is more particularly intended is disclosed in my prior Patent, No. 1,497,303, dated June 10, 1924. The objects of the invention are to provide an auxiliary fastening on the projecting keeper for cooperation with the casing of the main fastening or, to provide an improved shackle for securing the door while permitting it to be opened for a few inches, and to improve and strengthen the casing of the main fastening or lock.

20 In the accompanying drawings forming a part hereof:

Fig. 1 is an elevation of the main fastening or, keeper and shackle, the latter in an inoperative position on the inner side of a door and door casing, broken lines being used to show the blocking position of the auxiliary fastening on the keeper;

Fig. 2 is a horizontal section through Fig. 1, with the shackle and most of the casing of the main fastening or lock in elevation, broken lines being used to show the turned position of the auxiliary fastening on the keeper and different positions of the shackle arm;

Fig. 3 is a horizontal section on a smaller scale, showing the door ajar, with the shackle arm in sliding engagement with a projection on the casing of the main fastening or lock;

Fig. 4 is a fragmentary sectional bottom plan view of the shackle arm, its base plate and spring, showing the shackle arm yieldingly held in an inoperative position;

Fig. 5 is a fragmentary view looking toward the left of Fig. 4;

Fig. 6 is a sectional plan view on an enlarged scale of the keeper and its turning fastener-piece, the fastener-piece being shown in the cross position; and

Fig. 7 is a view looking at the inner end of the casing of the main fastening or lock with its shackle lug or projection and its twin bolts.

The door is indicated at 2, and the door jamb, door frame or wall is marked 3. For greater simplicity no attempt has been made to differentiate the door frame structure and

the wall, as these details are not essential to the invention. The casing 4 of the main fastening or lock is applied to the inner face of the door, to which it is secured by screws 5. The heads of these screws preferably rest in thickened portions 6 of the casing wall, these portions being connected by a framing rib 7 and the margin of the casing surrounding this rib being preferably bevelled as shown at 8. Inside the lock casing 4 is a twin bolt 9, 9 (Figs. 2 and 7), which is operable by a knob 10 on the inside of the door or by a key lock cylinder 11 on the outside, substantially as shown, for example, in my prior patent.

As in my said prior patent, the lock casing 4 has an integral extension 12 carried beyond the edge of the door so as to overlap the door frame. This extension comprises a vertical wall 13 spaced from the end wall 14 of the body of the lock casing 4 and strongly united therewith by integral top and bottom portions 15 and 16. The said walls 13 and 14 are provided with aligned openings 15 and 16 for the bolt.

The space or opening between the casing 4 and its extension receives, when the door is closed, a keeper lip 17, which projects from the door-jamb, inwardly of the apartment, that is to say in a direction at right angles to the plane of the door. This keeper is provided with similar bolt-openings 18 to register with the holes 15 and 16; and, when the door is locked, the twin bolt passes through the holes 16 in the end wall of the casing body, the holes 18 in the keeper and into or through the holes 15 in the extension wall of the lock casing, producing a very powerful lock. The extension wall 13 is formed, as in my patent aforesaid, with a face flange 19 and a rear flange 20, projecting endwise away from the lock casing and forming a channel guarding the ends of the bolt and greatly strengthening the structure.

In accordance with one part of the invention, as embodied in the specific lock illustrated, the face flange 19 is formed intermediate its upper and lower ends with a shackle lug or projection 21. This projection is preferably in the form of a key-hole eye, made as a thickened boss on the flange, extending beyond the edge thereof, and having a comparatively narrow lateral entrance 22 at its outer side communicating with the relatively enlarged hole 23 of the eye. In

other instances, however, the shackle lug may be of other form.

This lug is designed to cooperate with a swinging shackle arm 24, pivotally mounted 5 on the door-jamb or door-frame adjacent the door. The inner end of said arm is pivoted on a pin 25 between ears 26 on a base-plate 27, which is secured by screws 28 to the face of the door-jamb. It will be 10 seen that the location of the pivot of the arm 24 on the face of the door-jamb is beyond the closed-door position of the projection 21.

The shackle arm of the preferred embodiment consists of a round bar, longitudinally 15 curved the better to accommodate it to the arc of movement of the shackle lug 21 in the swinging of the door, and connected with the pivot by an offset, flattened shank 29. The offsetting of the body of the arm, 20 which is formed for sliding interengagement with the projecting eye 21, with respect to the portion 29, which is formed to pass into and out of engagement with such projection, together with the location of the 25 pivot of the arm beyond the closed-door position of the eye, is an advantage for reasons, including that the arm may be positioned and kept by the spring 35, hereinafter mentioned, out of the path of the projection, 30 without requiring the arm to be swung farther than may be permitted by the wall, when the door-jamb is located at a corner recess. The offsetting or angle between the 35 body 24 of the shackle arm and the entrance portion 29 is convex with respect to the lock-casing, that is to say the outside, not the inside of the angle, is toward the lock.

The shackle-arm when disposed in the full-line positions of Figs. 1, 2 and 4 or in the intermediate broken-line position of Fig. 2, is out of action and the door can be 40 opened and closed freely without reference to the shackle. When, however, the shackle-arm is swung to a position in the path of the shackle-lug, which position is represented by the extreme broken-line position of Fig. 2, the narrow shank 29 is in operative registry with the entrance 22, and when the door is partly opened, the ends 45 of the eye 21 will receive the shank between them, and the eye will be guided onto and slide over the round bar 24, which is too large to pass out through the entrance. A ball enlargement 30 on the free end of the 50 arm prevents further movement when the eye encounters this ball, the door then being securely fastened at its few inches of opening. The construction is such as to be not only very strong, but neat and unobtrusive in an apartment. For further 55 strengthening a cross-rib 31 is formed on the outer face of the extension wall 13, between the twin bolt holes, joining the flanges 19 and 20 at the region of the shackle-lug 21.

The pivoted end of the arm 24 is formed with three flat spring seats 32, 33, 34, disposed in a particular manner, to cooperate with a positioning and yielding-holding spring 35 in the base plate 27. When the 70 arm is turned so that the seat 32 is in contact with the spring, the arm is yieldingly held in position to be engaged by the shackle-lug when the door is opened. When the arm is in position with either the seat 75 33 or the seat 34 in contact with the spring, the arm is yieldingly held out of the path of the shackle-lug on the lock casing. In the full line position of Figs. 1 and 2, in which the spring 35 bears against the seat 80 34, the arm lies against the wall. The intermediate seat 33 is provided for those cases in which the arm may have to stand in the corner of a wall. Instead of a slotted shackle-lug with entrance on the lock casing, and a headed rod on the door-casing, there may in some cases be a reversal in the 85 forms, but the construction shown is preferred.

According to another part of the invention, the projecting lip 17 of the bolt-keeper is utilized for the application of an auxiliary fastening to overlie the lock-casing and prevent opening of the door, even if the bolt should fail, or if an unauthorized person 90 should with a key or other means succeed in unlocking the fastening proper. This auxiliary fastening is on the inside of the apartment and affords an additional neat bolt or bar for direct manual operation, involving little additional expense and not encumbering either the appearance or the 95 mechanism of the lock. The particular construction may be varied; but, in the best embodiment, an oblong piece 36 is provided, 100 which may have the appearance of simply being the end of the keeper projected somewhat beyond the face of the casing 4. Interengagements are provided on the keeper 105 110 115 120 125 130 135 140 145 150 155 160 165 170 175 180 185 190 195 198 199 200 201 202 203 204 205 206 207 208 209 210 211 212 213 214 215 216 217 held by the increased tension of the spring. The turn-piece now overlaps the body and the extension of the lock casing, offering excellent resistance to opening of the door.

5 The keeper, as in my prior patent, is provided with flanges 41 and 42, at right angles to each other, applied to faces of the door-jamb, to which they are secured by screws 43, 44.

10 While the preferred embodiment of the invention has been described in detail, I do not wish to be limited to the precise details, arrangement and combination, since parts may be varied in form and relation, or may 15 be used without others.

I claim:

1. The combination in and with a main door fastening having a casing designed to be applied to the inner face of a door and 20 formed with an integral extension spaced from and in line with the body of the casing to overlap the door-frame, with a bolt in the casing adapted to be projected across from the body of the casing into said extension 25 through a bolt-keeper projecting from the door-jamb and intervening between the body of the casing and said extension, of a projection formed with said extension, and a swinging shackle arm pivotally mounted on 30 the door-jamb, said projection and arm formed for sliding interengagement to the extent limited by the arm and for engagement and disengagement of the arm with the projection when the door is in closed 35 position.

2. The combination in and with a main door fastening having a casing designed to be applied to the inner face of a door and 40 formed with an integral extension spaced from and in line with the body of the casing to overlap the door-frame, with a bolt in the casing adapted to be projected across from the body of the casing into said extension through a bolt-keeper projecting from the 45 door-jamb and intervening between the body of the casing and said extension, said extension having a face flange, of a projection formed with said face flange, and a swinging shackle arm pivotally mounted on the door-jamb, said projection and arm formed for 50 sliding interengagement to the extent limited by the arm and for engagement and disengagement of the arm with the projection when the door is in closed position.

55 3. The combination in and with a main door fastening having a casing designed to be applied to the inner face of a door and 60 formed with an integral extension spaced from and in line with the body of the casing to overlap the door-frame with a bolt in the casing adapted to be projected across from the body of the casing into said extension through a bolt-keeper projecting from the 65 door-jamb and intervening between the body of the casing and said extension, of an eye

formed with said extension and provided with a lateral entrance, and a swinging shackle-arm pivotally mounted on the door-jamb, said arm formed to be slidingly retained in said eye and having an inner shank 70 portion capable of passing through said entrance.

4. The combination of a main door fastening comprising a casing applicable to a door and containing rectilinearly movable bolt 75 mechanism to cooperate with keeper means on the door-jamb, said casing having an extension to project over the door-jamb, a swinging shackle arm pivotally mounted on the door-jamb, said extension and arm being 80 formed for sliding interengagement to the extent limited by the arm so that the door may be opened to that extent and no further, and being also formed for engagement and disengagement of the arm with respect to the 85 extension when the door is in closed position, the pivot of said shackle arm lying beyond the closed-door position of said extension, and the body of the arm which is formed for sliding engagement with the projection being 90 convexly offset with respect to the portion of the arm which is formed to pass into and out of engagement with the projection and with respect to said casing.

5. The combination of a main door fastening having a casing designed to be applied to the inner face of a door and formed with an integral extension to overlap the door-frame, said extension having twin bolt openings with a twin bolt in the casing adapted 100 to be projected across from the body of the casing into said extension through an intervening bolt keeper projecting from the door-jamb, said extension having a face-flange, a projection on said face-flange, a transverse 105 rib on the extension of the lock casing disposed between the twin bolt openings and joining said flange at the region of said projection, and a swinging shackle arm pivotally mounted on the door-jamb for cooperation 110 with said projection, substantially as set forth.

6. The combination in and with a main door fastening having a casing designed to be applied to the inner face of a door and 115 formed with an integral extension to overlap the door-frame, with a bolt in the casing adapted to be projected across into engagement with the extension, and an outstanding bolt-keeper lip constructed to be received between the body of the lock casing and 120 said extension, of a turn-piece on the end of said keeper lip adapted to lie either with or outwardly of the lip, in the latter position constituting a block opposed to the lock casing.

7. The combination of a main door fastening having a casing designed to be applied to the inner face of a door and formed with an integral extension to overlap the door-frame, with a bolt in the casing adapted to 130

4
be projected across into engagement with the extension, an outstanding bolt-keeper constructed to be received between the body of said casing and said extension, and auxiliary fastening means on the outer part of said keeper lip adapted to be disposed across said casing.

8. In a door fastening, the combination with a bolt casing and an outstanding bolt-
10 keeper lip, of an auxiliary locking piece on the inner end of said lip adapted to be turned over said casing, a pivot pin securing said piece to the keeper lip and permitting slight movement toward and from the same, inter-
15 engagements on said piece and lip to keep

the piece in unobstructing position, and a spring pressing the piece to the lip and in engagement with said means.

9. In a door fastening, the combination with a bolt casing and an outstanding bolt-
keeper lip, of an oblong auxiliary fastening piece adapted to lie either with or across the keeper lip, in the latter position constituting a block opposed to said casing, a pivot securing said piece to the keeper-lip, said piece and lip being formed with tongue and groove, and a spring between said pivot and piece pressing the latter into engagement with the lip. 20
